UNITED STATES PATENT OFFICE.

WILTON E. DARROW, OF SUTTER CREEK, CALIFORNIA.

ADJUSTABLE SWINGING SPRAY FOR MINERAL-WASHING.

1,123,254.

Specification of Letters Patent.

Patented Jan. 5, 1915.

Application filed March 23, 1914. Serial No. 826,486.

To all whom it may concern:

Be it known that I, WILTON E. DARROW, a citizen of the United States, residing at Sutter Creek, in the county of Amador and 5 State of California, have invented certain new and useful Improvements in Adjustable Swinging Sprays for Mineral-Washing; and I do declare the following to be a clear, full, and exact description of the same, 10 such as will enable others skilled in the art to which it appertains to make and use the same, reference being had to the accompanying drawings, and to the characters of reference marked thereon, which form a part 15 of this application.

This invention relates to improvements in paraphernalia used in connection with the concentration of slime crushed ores, the object of the invention being to produce a 20 spraying means for washing off and collecting the valuable mineral concentrated.

The device is particularly designed for use with a plurality of sprays arranged in series one above the other, as shown in Patents Nos. 898,331 and 906,205, dated September 8th, 1908 and December 8th, 1908, respectively, or in devices of a similar type, and the aim of my present invention is to produce such a spray as will wash over the 25 table and at the same time move up and down with respect to the grade of the trays in order to fully cover the entire surface of the trays with water and in such a manner as to remove the accumulated mineral as fast 30 as the rotation of the concentrating device brings the loaded surfaces of the trays past the spraying zone.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a side elevation of my complete spraying mechanism. Fig. 2 is a plan view thereof. Fig. 3 is a rear elevation thereof.

Referring now more particularly to the characters of reference on the drawings, the numeral 1 designates the main supporting post of the spraying mechanism which is

disposed in an inclined manner with respect to the concentrating trays 2 and journaled at its top and bottom to allow of a rotary motion.

Projecting from a point near the bottom of the post 1 is a pipe 3 having a flexible connecting hose 4 for connecting it with any suitable water supply. At the outer end of said pipe 3 is a ball and socket joint 5 by means of which a vertical pipe 6 is connected with the pipe 3 which projects at substantially right angles to the pipe 3 and parallel with the vertical plane of the trays 2, said pipe 6 being journaled at its upper end, as at 7, in a projecting arm 8 swiveled at its other end as at 9, which arm 8 projects in a parallel manner with respect to the pipe 3 for the purpose of maintaining the pipe 6 in a substantially vertical position at all times irrespective of its movement hereinafter described. On the upper end of the pipe 6 is a projecting arm 10 for a purpose as will presently appear.

Communicating with the pipe 6 are a plurality of independent spray pipes 11 each projecting over one of the trays 2 and being provided with one or more discharge nozzles 12.

Connected with the pipe 6 are a pair of rearwardly projecting arms 13 into which hook pitmen 14, each of said pitmen being connected with a crank 15, such cranks 15 being mounted on a shaft 16 having a driving pulley 17 for connection with any suitable motive power.

The connections of the pitmen 14 with the cranks 15 are made adjustable by such pitmen having a plurality of holes 18 to receive bolts 19 by means of which the pitmen may be connected with the cranks at different points as will be readily seen.

The numeral 20 designates a rod adapted to be connected with the arm 10 and fixed at the other end at any desired point such as at 21, all for a purpose as will presently appear.

In practice, water is admitted through the member 4 or members 3 and 6 and the same passes out through the members 11 to the spray nozzles 12 which discharge upon the trays 2. In order to thoroughly wash the trays it becomes necessary to give these nozzles 12 a swinging motion and at the same time a slightly upward and downward motion over the surface of the trays and this is accomplished as follows, namely: Pre-

suming the rod 20 is not connected with the arm 10, rotary motion is imparted to the pulley 17 which drives the shaft 16 and the cranks 15 to operate the pitmen 14. The 5 post 1 then forms a pivot upon which the entire spraying mechanism swings and swinging on that point and its own end bearings, the pipe 6 would move in an arc described substantially by the line "a" 10 shown in Fig. 2, which movement by reason of the inclined position of the member 1 and the position maintained for the member 6 by means of the arms 3 and 8 would cause the spray nozzles 12 to move up and down 15 over the trays 2 and at the same time describe a motion over the surface of the trays 2 substantially the same as that designated by the line "b" in Fig. 2. When however it is desired to move the said 20 spray pipes 11 in a fixed arc, the rod 20 is connected with the arm 10 and with its fixed point 21 which will cause the rod 20, the arm 10 and the arms 8 and 3 all to swing in the same arc with the member 1 25 as their pivot which will then cause the spray nozzles 12 to move over the surface of the trays 2 in substantially the arc designated by the letter "c" in Fig. 2.

From the foregoing description it will 30 readily appear that by means of my improved spraying mechanism, I can spray the entire surface of each of the trays 2 with a very short movement of the spray pipes 12 over the surface thereof which 35 can be adjusted as desired by increasing or decreasing the number of spray nozzles 12, the idea being to keep a continual spray against the surface of each tray from the extreme upper end to the extreme lower end 40 thereof in order to thoroughly wash the valuable slimes therefrom.

From the foregoing description it will 45 readily be seen that I have produced such a device as substantially fulfills the objects of the invention as set forth herein.

While this specification sets forth in de-

tail the present and preferred construction of the device still in practice such deviations from such detail may be resorted to as do not form a departure from the spirit of 50 the invention.

Having thus described my invention what I claim as new and useful and desire to secure by Letters Patent is:—

1. A device of the character described 55 comprising the combination with a concentrating table, of a spraying means mounted upon an axis, and means for reciprocating the spraying means longitudinally across the table and means for causing it simultaneously to describe an arc laterally with respect to the table, as described.

2. A device of the character described comprising the combination with a concentrating table, of an inclined spindle, an arm 65 on such spindle, a vertical member projecting upwardly from the outer end of said arm, said vertical member having an independent movable bearing at its upper end, spraying members projecting from said vertical member over the surface of said table, as described, and means for oscillating said spindle.

3. A device of the character described comprising the combination with a concentrating table, of a spindle, an arm mounted 75 on said spindle, a vertical member on said arm, an independent movable bearing on the upper end of said vertical member, a rod flexibly connected with said arm at one end 80 and at an independent point at its opposite end, a spraying means mounted on said vertical member and projecting over the surface of said concentrating table, and means for oscillating said spindle as described. 85

In testimony whereof I affix my signature in presence of two witnesses.

WILTON E. DARROW.
